UNITED STATES PATENT OFFICE.

SAMUEL SHREFFLER, JR., OF JOLIET, ILLINOIS.

PARLOR-DOOR HANGER.

SPECIFICATION forming part of Letters Patent No. 281,308, dated July 17, 1883.

Application filed January 20, 1883. (No model.)

To all whom it may concern:

Be it known that I, SAMUEL SHREFFLER, Jr., a citizen of the United States of America, residing at Joliet, in the county of Will and 5 State of Illinois, have invented certain new and useful Improvements in Parlor-Door Hangers, of which the following is a specification, reference being had therein to the accompanying drawings.

10 Figure 1 is a side elevation; Fig. 2, a vertical section of the upper end of the door having the hanger applied thereto; Fig. 3, a vertical cross-section on line X of Fig. 1; Fig. 4, a perspective view of the lower end of one of 15 the diagonal slides, a^2 ; and Fig. 5 a perspective view of the slide P.

This invention consists in the mode of adjusting the rider-bar a of the door-hanger up or down, so as to cause the door B to hang 20 plumb.

Referring to the drawings, B represents the door, having a rider-bar, a , attached at each upper corner of the door, which rider-bars a ride upon the axle of the double tread-wheels 25 $c c$ on the tracks D D. The lower parts of the rider-bars are provided with diagonal slides a^2 a^3 , which pass down through a metal plate, a' , having suitable slots in it to permit the slides to pass down through, as shown particularly in Fig. 2. The metal plate a' passes 30 over the corner of the door downward, as shown in said Fig. 2, to make it firm and furnish a seat for the set-screw s to turn in. The slide a^2 of the rider-bar a is provided with lugs 35 d , as shown particularly in Fig. 4, extending each way.

The slide P (shown in perspective in Fig. 5) is placed immediately beneath the metal plate a' , as shown in Figs. 2 and 3, so its slot 40 P ^{2} will be directly beneath and correspond with the slot in plate a' , through which the slide a^2 passes. The slide a^2 passes down through slot P ^{2} of the slide P. This slide P is movable horizontally under the plate a' by 45 means of the set-screw s , and as it moves, the lugs

d on the slide a^2 impinge against the inclines P' in the slide P. When the set-screw is turned it will draw the slide P toward the corner of the door, pulling the inclines P' up under the lugs d , thereby elevating the door at that corner, as is obvious from the construction of the parts. When the set-screw s is unscrewed, of course the slide P will move backward, permitting the lugs d to slide up the inclines P', and thereby lower that corner of the door. It is intended to furnish either corner of the door with these slides P, so each corner may be elevated or lowered alike. The slide P slides in proper channels formed on the under side of the plate a' , so they cannot become disarranged. It is in the use of this slide P, in connection with the lugs d on the slide a^2 , that this invention consists.

I am aware similar slides have been used on such a rider-bar, but none having the lugs d arranged to operate with such a slide, P.

In order to prevent the rider-bar a from rubbing along against the inner sides of the tracks D, I provide the tracks with flanges z on the inner-sides next the rider-bar, instead 70 of having any flanges on the wheels. This is a much better construction than flanges on the wheels, and keeps the rider-bar directly in the center between the tracks, as shown in Fig. 3.

Having thus described my invention, what I claim as new, and desire to secure by Letters Patent, is as follows, to wit:

In a parlor-door hanger, the combination of the slide P, having the slot P ^{2} , and inclines P', set-screw s , rider-bar a , plate a' , and slide a^2 , having the lugs d , all adapted to operate as and for the purpose set forth.

In testimony whereof I affix my signature, in presence of two witnesses, this 17th day of 85 January, 1883.

SAMUEL SHREFFLER, JR.
